WARP LETOFF MOTION

Edward Kinsella, Spondon, near Derby, England,
assignor to Celanese Corporation of America, a
corporation of Delaware

Application November 27, 1940, Serial No. 367,331
In Great Britain December 28, 1939

4 Claims. (Cl. 139—110)

This invention relates to improvements in warp let-off motions. The let-off motion according to the invention is particularly well adapted for use in circular looms designed for the production of dress fabrics and other high quality fabrics.

A warp let-off motion according to the invention comprises a warp-beam carriage movable in the direction in which the yarn leaves the beam, means to urge the carriage in a direction opposite to that in which the yarn leaves the beam, means for rotatably mounting a beam in the carriage, friction gearing in driving connection with the beam mounting, the gearing comprising a driver member adapted to be constantly rotated and a driven member movable to variable radial distances with respect to the driver member, and means connecting the beam carriage to the driven member to enable the radial distance at which the driven member contacts with the driver member to be governed by movements of the beam carriage in response to variations in the tension of the yarn.

The driving connection from the friction gearing to the beam mounting includes worm or other reduction gearing to enable the beam to be rotated at the relatively slow rate necessary to deliver yarn at the rate at which it is consumed, while permitting the friction gearing to operate at an efficient speed. The friction gearing may conveniently be in driving connection with the take-up motion, since let-off and take-up rates are necessarily correlated.

By means of the motion according to the invention an increase in the yarn tension causes the beam carriage to move so as to increase the radial distance at which the driven friction member contacts with the driver member, with the result that the beam is driven at proportionately increased speed. With the resultant increased delivery of yarn from the beam, the yarn tension is reduced and the driven member returns towards the centre of the driver member. Consequently, a constant adjustment of tension is provided, notwithstanding the variation in the diameter of the body of yarn on the beam as weaving proceeds.

In the case of a circular loom, weaving proceeds continuously round the circumference of the loom, and all the essential mechanisms receive movements of simple rotation. Accordingly, therefore, the driver friction member for the let-off mechanism may be directly coupled to some suitable part of the main driving mechanism of the loom to provide a continuously available drive for the warp supply.

The beam carriage should be capable of free movement so as to be quickly sensible to changes in yarn tension, and advantageously the carriage is arranged to roll, with freely rotatable wheels, along suitable rails. Stops may be provided to limit the extent of movement of the carriage in either direction, and advantageously a wiper contact is provided by means of which a stop motion is rendered operative in the event of excessive movement of the carriage, especially under conditions of particularly high yarn tension.

With a sensitive fully-compensating let-off mechanism of the character described above, and with the usual type of continuously-driven take-up mechanism, a circular loom is enabled to weave fabric of particularly high quality. In addition the let-off mechanism is helpful in avoiding bars in the fabric resulting from gradual stretch of the yarn during any fairly prolonged stoppage of the loom.

A form of let-off mechanism according to the invention as applied to a circular loom employing four warp beams will now be described in greater detail with reference to the accompanying drawings, in which

Figs. 1 and 2 are diagrammatic plan and elevation views showing the general construction of a circular loom.

Fig. 3 is an elevation to a larger scale of the let-off mechanism taken on the line 3—3 of Fig. 4; and

Fig. 4 is a plan view of part of Fig. 3.

The warp supply is placed on top of the loom frame, which comprises four vertical columns 1 tied rigidly together by an X-member 2. Brackets 3 on the columns 1 provide a solid support for four rollers 4, over which the four warps are led from the beams 5 and turned downwardly before being constrained into cylindrical form over the vertical length 6 for the insertion of weft by the several shuttles of the loom, of which two are seen at 7. The fabric 8 proceeds to the take-up motion 9 at the foot of the loom. The four guide rollers 4 occupy the sides of a square within the square bounded by the four columns 1. The warp beams 5 are supported on brackets 10 formed by angle-irons 11 extending horizontally beyond the four columns. Each bracket 10 carries a rail 12 on which wheels 13 on the end frame 14 of the beam carriage 15 run, the two frames 14 being connected by rods 16. Rotatable tubes 17 surrounding the two lower rods 16 carry the beam flanges and permit the beam to rotate easily.

At the outer end of each bracket 10 is secured

a sprocket 18, over which passes a chain 19 connected at 20 to one of the end frames 14. The chain 19 passes round a sprocket 21 pivoted on a shaft 22 on the bracket 10 and secured to a sprocket 23 of twice the diameter. The end of the chain 19 is secured at 24 to the sprocket 23. Another chain 25 secured to the sprocket 23 at 26 passes round the sprocket and carries removable weights 27.

The run of the chain 19 from the sprocket 18 to the point of attachment 20 to the beam carriage 15 is horizontal, at a height substantially midway between the heights at which the yarn leaves the top of the beam when the beam is full and empty respectively. The pull of the two chains at the ends of each beam carriage determines the warp tension, and the differential sprockets 21, 23 permit small, easily handled weights 27 to be applied to the chain 25 to bring about the required tension.

Near one end frame 14 a worm wheel 28 is mounted and a detachable driving member 29 enables a warp beam 5 placed between the end frames to be rigidly connected to the worm wheel. A worm 30 mounted on a horizontal shaft 31 meshes with the worm wheel. The shaft 31 is connected by a flexible coupling 32 to a shaft 33 to the end of which is secured a friction wheel 34 whose edge makes contact with the face of a driver friction wheel 35 mounted on a vertical shaft 36 in a subsidiary frame 37 carried by the member 2. The four driver friction members 35 are driven by a single chain 38 passing round sprockets 39 on their respective shafts 36, sprockets 40 on the member 2, and a sprocket 41 on a vertical shaft 42 geared to the main loom mechanism through suitable adjustable reduction gearing 43. A universal coupling 44 on the shaft 42 provides for the driving of the take-up motion 9, and a hand-wheel 45 enables the let-off and take-up motions to be operated by hand.

The main drive shaft 42 rotates at such a speed that in conjunction with the reduction offered by the worm gearing 28, 30 the requisite amount of yarn is let-off when the driven friction wheels 34 are engaging an intermediate range of the surfaces of the driver friction wheels 35, the compensation provided being sufficient in any case to deal with the different rates of angular rotation of the warp beams necessary to allow for the diminishing diameter of the beam as weaving proceeds. The gear 43 included in the main shaft drive allows for a wide range of let-off rates.

Referring to Fig. 3, it will be apparent that if the tension in the warps increases, the pull of the warps between the roller 4 and the beam 5 will move the carriage 14 to the right against the urge of tension of the chain 19 in the opposite direction. The shafts 31, 33 also move to the right and the driven wheel 34 on the shaft 33

moves towards the periphery of the driver wheel 35. The wheel 34 is therefore driven faster and the rotation of the beam 5 increases correspondingly to deliver yarn at a greater rate towards the roller 4 until the tension is again balanced by the pull in the chain 19.

At the outer ends of the brackets 10 stops 46 are provided to prevent over-running of the carriages in the event of a smash. Similarly, stops 47 may be provided at the inner ends of the brackets to limit the movement of the carriages in the event of excessive warp tension. However, in order to prevent damage to the warps one of each pair of brackets carries a contact strip 48 over which a wiper 49 moves, so as to break the connection between leads 50 and thereby operate a stop mechanism (not shown) in the event of excessive inward movement of the carriage. Hooks 51 depending from the end frames of the carriage prevent accidental lifting of the carriage from its rails 12. Strong safety chains 52 hanging loosely from the brackets 10 to the weights 27 prevent falling of these weights in the event of breakage of one of the chains connecting the weights to the carriage.

Having described my invention, what I desire to secure by Letters Patent is:

1. Warp let-off motion comprising a warp-beam carriage movable in the direction in which the yarn leaves the beam, means to urge the carriage in a direction opposite to that in which the yarn leaves the beam, means for rotatably mounting a beam in the carriage, friction gearing in driving connection with the beam mounting, the gearing comprising a driver member adapted to be constantly rotated and a driven member movable to variable radial distances with respect to the driver member, and means connecting the beam carriage to the driven member to enable the radial distance at which the driven member contacts with the driver member to be governed by movements of the beam carriage in response to variations in the tension of the yarn.

2. Warp let-off motion according to claim 1, comprising rails, and rollers on the beam carriage to enable the carriage to roll along the rails in response to variations in the tension of the yarn.

3. Warp let-off motion according to claim 1, comprising rails, rollers on the beam carriage to enable the carriage to roll along the rails in response to variations in the tension of the yarn, and stops to limit the movement of the carriage along the rails.

4. Warp let-off motion according to claim 1, comprising means to render a stop motion operative in the event of excessive movement of the beam carriage.

EDWARD KINSELLA.
